COKING PITCH

Application filed December 28, 1929. Serial No. 417,078.

This invention relates to the production of coke from pitch. According to this invention, a coke mass is produced by gradually supplying pitch to a coking vessel and coking it therein through indirect heating means, and as the mass of coke increases by the addition of pitch and its conversion to coke, the zone of the coking vessel to which the heat is applied is changed so that the area of intense heating is extended upwards following the increase in height of the oven charge; the heat supply to the lower part of the oven may eventually be reduced since this part of the charge will be completely coked before the upper part.

Various methods have been suggested for converting pitch to coke. According to some of these methods, a large body of pitch is heated and converted to coke. On heating such a large body, convection currents are set up within the body and gases and vapors are given off with resultant ebullition of the body which interferes with the formation of a compact and solid coke such as is desirable for metallurgical purposes, causes stoppages of gas outlets by the foam produced and has other operating drawbacks. Processes which involve agitation of the pitch or coke during the coking process and processes which involve continuously moving the mass of coking material, such as continuous processes in which pitch is supplied to one end of a coking vessel and the coke produced is withdrawn from the other, tend to prevent the formation of large pieces of strong compact coke suitable for metallurgical or foundry purposes. According to the present process the coking is conducted while the pitch is maintained substantially stationary, that is, it is not agitated by outside means or continuously passed through a coking vessel. Some motion of the pitch may take place due to the nature of the pitch and of the reactions occurring during coking. However, only a small body of pitch is present in the coking vessel at any

one time and that which is present is on top of the charge so that disturbances within the pitch due to convection currents and ebullition are reduced to a minimum.

According to this invention, pitch may be converted to coke in an oven such as a coke oven or an oven similar in construction to a coke oven. The bottom portion of the oven is heated and pitch is added to the oven and the temperature of the pitch is raised to the coking temperature. Additional pitch is gradually added to the oven. The pitch may be added to the oven continuously as by adding the pitch gradually in a continuous stream, or small amounts may be added at spaced intervals, or larger amounts, e. g. one quarter to one third of the charge may be added at one time. As the pitch is added to the oven and the material in the oven is coked, the zone of maximum heating is extended upwards so that intense heat is applied to the freshly added pitch and to the coking mass; furthermore, it may be desirable to reduce the amount of heat supplied to the lower portions of the oven, where the coking is completed earlier than at the top.

The oven in which pitch is coked, according to this invention, is advantageously constructed of fire-brick, silica brick, etc. It is heated by means of flues embedded in the walls of the oven, and there may also be flues in the sole of the oven. A single oven may be employed or all or several ovens of a battery may be used simultaneously. When more than one oven is employed, the ovens may advantageously be charged in series, and when the coking has been completed, they will then be pushed in series and recharged. When individual ovens of a series are employed in this manner they are advantageously equipped with separate heating flues, but when several ovens are employed and all of the ovens are charged and pushed at substantially the same time, the same heating flues may be employed for heating two

adjacent ovens. The ovens may be heated in any suitable manner. Valve means may be provided to direct the hot flue gases through any selected flues, and to shut them off from other flues, and to change the flues through which the hot flue gases are passed, as desired; or a bank of continuous flues may be employed with burners for raising any selected flue or flues to intense heat.

10 Pitch may be coked in the ovens of an ordinary coke oven battery, according to this invention. The individual ovens of a coke oven battery are ordinarily heated by the combustion of gas, etc., with preheated air, and the regenerator or recuperator in which the air is preheated is common to the ovens of the battery. In a battery of coke ovens of the Semet-Solvay type, for example, it is customary to preheat the air in a regenerator, and this preheated air is admitted to the heating flues which are ordinarily arranged horizontally. The heated air is admitted alternately to the top flue and the bottom flue. The arrangement of the flues and air passages is such that when the valves controlling the flow of waste gases and air through the regenerators are shifted to change the direction of flow of the air and waste gases, the preheated air which is introduced into the upper flue, for example, is then introduced into the bottom flue, or vice versa, and hot waste gases which escape through the bottom flue then escape through the upper flue. This change is made at regular intervals of, for example, thirteen or fifteen minutes. This change in the flow of the preheated air and the hot waste combustion gases through the flues, provides increased combustion efficiency by affording a supply of preheated air for the burners, but prevents burning out of the regenerators through overheating. By varying the position in the flues in which the most intense combustion takes place, the area of intense heating may be changed. This 45 Semet-Solvay type of oven, which is equipped with horizontal flues, is particularly well adapted to the coking of pitch according to this invention.

50 The ovens may be rectangular in cross-section, or they may taper toward the top or toward the bottom, or the ovens may taper toward one end to aid in pushing the coke from the ovens.

55 The pitch to be coked may be produced by the distillation of tar, or it may be pitch which has been directly recovered from hot coal distillation gases by cleaning them at a high temperature, or pitch resulting from a combination of these two processes may be coked. Pitch of high melting point, for example, pitch with a melting point of 350 or 400° F. or even higher, is to be preferred to pitch of lower melting point. Lower melting point pitches are advantageously distilled to pitches of higher melting point in appara-

tus designed for the production of these higher melting point pitches before being subjected to the coking operation contemplated by this invention. Pitches of higher melting point are to be preferred since there is less danger of foaming with such higher melting point pitches and these pitches are more readily and rapidly transformed to a plastic or solid mass, and the possibility of leakage through the walls and sole of the oven is thus reduced.

The pitch is advantageously added to the oven in a melted condition and preferably in a hot, thinly fluid state. Such pitch readily spreads over the mass of coking material in the oven. Where necessary any suitable means for spreading the pitch may be employed. Pitch may be added to the oven in solid form where desirable.

According to a preferred method of carrying out the invention, the oven is first heated by passing hot combustion gases through flues at the bottom of the oven. These flues may be located in the sole of the oven or at the bottom of the side-walls, or the hot gases may be passed through flues located both in the sole of the oven and at the bottom of the side-walls.

When an oven is employed for coking successive batches of pitch, the first portion of each successive batch is advantageously charged to the oven before the heat supplied to the oven in coking the previous batch has been entirely dissipated and while the oven is still at a high temperature. It is advantageous to keep the walls of the oven at a relatively high temperature at all times since repeated heating and cooling of the walls over considerable temperature ranges is liable to produce cracks in the walls and sole of the oven. When the pitch is coked in ovens of a battery of the Semet-Solvay type, the preheated air and hot waste gases passing through the flues keep the oven walls hot at all times.

The pitch is added to the oven gradually, and after the pitch first added to the oven has been heated to a coking temperature and formed a mass of solid or semi-solid coke or semi-coke, sufficient additional pitch is added to the oven to form a layer of pitch on the already formed semi-coke or coke over the whole area of the oven. Pitch is thus advantageously added in increments while the coking proceeds until the entire charge is added to the oven. As the mass of coking material on the bottom of the oven becomes too deep to allow efficient transfer of heat from the bottom flues to fresh increments of pitch added on top of the coking mass, flues above the bottom flues are successively brought to high temperature. The temperature of the combustion gases passing through the flues at the bottom of the oven may subsequently be considerably reduced. As the coking pro-

ceeds and added increments of pitch are coked, the mass of coke in the oven increases and the oven is filled more and more with coke and the coking mass. As the layer of coke builds up in the oven, and the mass being coked, which is on top of the mass of coke already produced in the oven, becomes further and further removed above the hottest flues, the flues next above these are brought to high temperature and eventually the temperature of the gases passing through the lower flues may be reduced or the introduction of fuel gases into these flues may be discontinued entirely. As the operation progresses, the heating zone may thus be extended upwards and its upper limit is maintained at a level in proximity to the level of the added increments of pitch being coked. Its lower limit may eventually be moved upwards when the lower part of the charge is completely coked.

The amount of pitch added at each interval may be varied as desirable. Each added increment may measure a fraction of an inch on the vertical walls of the oven or as much as several inches of pitch may be added at one time. When a considerable amount of pitch is added to the oven at one time, the material in the oven is advantageously coked to the point where it produces a solid mass before additional pitch is added. When the increments are small, the coking need not proceed as far before additional fresh pitch is added to the oven.

In thus converting pitch to coke, oils are distilled from the coking mass and gaseous constituents are evolved which are valuable as fuel. The gases and vapors which are given off by the coking mass are advantageously collected and cooled to separate the oils which will include oils of higher boiling range and greasy and resinous constituents, and the fixed gases may be collected in a gas holder for use as fuel. When several ovens are operated simultaneously the gases may advantageously be collected in a gas collector main similar to that employed in connection with a battery of coke ovens, and the combined gases passed from the collector main to a condensing system, not shown.

When clean oil products are desired, the gases may advantageously be cleaned while at a high temperature either in an electrical precipitator or in a suitable hot pitch scrubber so that on cooling the hot cleaned gases clean oils will be recovered directly from the gases.

After the pitch is coked, it is removed from the oven in any suitable manner, as for example, by pushing the coke with a pusher similar to that employed for the removal of coke from coke ovens. The coke obtained is a solid compact coke of low ash content. It is suitable for metallurgical processes and

for other processes where such a coke is desired. It is readily obtained in large pieces and by careful handling and classification only a limited amount of fines will be produced.

The invention will be further described in connection with the accompanying drawings, which show adjacent ovens of a battery at different stages of the coking operation.

Fig. 1 is a vertical section through a battery of ovens; and

Fig. 2 is a section on the line 2—2 of Fig. 1.

The drawings show five ovens, A, B, C, D, and E. The height of each oven chamber is relatively greater than the width and so also is the height of the final coke bed produced in each oven greater than its width. Pitch is supplied to the ovens through pipes 21 inserted through the charging holes 22. An uptake pipe 23 is provided for removing gases and vapors evolved during the coking of the coal. The gases and vapors are conducted to a condensing system (not shown) for the recovery of tar products. The drawing shows heating flues, 1a, 2a, 3a . . . , 6a, 1b . . . , 6e embedded in the side walls of each of the ovens. The lowermost flues are indicated at 1a, 1b, etc.; the intermediate flues are shown at 2a, 3a, 4a, 5a, 2b, etc.; and the top flues are shown at 6a, 6b, etc. The number of flues in the wall of each oven may be varied as desired, and flues common to two adjacent ovens may be employed, or separate flues for each oven may be employed, as shown in the drawings.

Below the ovens are regenerator chambers 10. The regenerators are operated in pairs and are provided with valves (not shown) of the usual type so that after the hot waste combustion gases have heated the brick 11 in one regenerator, and the air for combustion has cooled the brick in a second regenerator, the hot waste combustion gases are passed through this second regenerator, reheating it, and the air for the combustion is passed over the hot brick in the first regenerator, the air being thus preheated. After sufficient time has passed to heat the brick in the second regenerator, the flow of waste gases and air is reversed so that the waste gases again flow through the first regenerator and the air is preheated in the second regenerator. This apparatus is of the usual type and is not shown in detail.

The passage 12 of Fig. 2 connects with one regenerator and the passage 13 extends down through the wall between adjacent ovens and connects with the second regenerator. When the flow of air and gases is up through the flues, as indicated by the arrows in the drawings, preheated air from the regenerator enters at 12. The amount of air admitted is regulated by proper valve means, such as a brick which partially covers one of the flues,

and the amount of air is adjusted to provide that necessary for combustion at those burners which are lighted. The hot waste combustion gases escape through the flue 13 to a 5 regenerator which they heat. When the flow of air and gases is reversed, air which has been preheated by passage through the last mentioned regenerator enters at 13 and, after passing down through the flues and 10 effecting the desired combustion, is exhausted through the flue 12 to the regenerator.

The flue 14 is heated by hot waste combustion gases which pass from the upper flues 15 down through the flue 14 at intervals, totaling in all about one-half of the coking period, and the bottom of the oven is thus kept at an elevated temperature throughout the coking 20 operation.

20 During the coking operation a selected portion of the oven is subjected to intense heat by the combustion of gas in one or more burners located in the flues and the portion 25 subjected to intense heat is changed as the coking progresses. During the early portion of the coking operation the flues at the bottom of the oven are raised to intense heat by burners in these bottom flues and as pitch is 30 added to the ovens and the level of the pitch in the ovens rises, the zone of intense heating is raised by lighting burners in higher flues. As the pitch is coked, the burners which heat that portion of the oven in which coke has 35 formed may be extinguished. The coking operation may be so controlled, for example, that pitch in the bottom of the oven heated by the burners 16 will be coked before pitch is added to the upper portion of the oven 40 heated by the burners 17, and the burners 16 may be extinguished after the burners 18, 19 and 20 have been lighted in succession and before the last portion of the charge of pitch has been added to the oven and before the 45 burners 17 are lighted.

When the preheated air and gas flow up 50 through the flues, as indicated by the arrows in the drawings, the flame from each of the burners will heat the upper of the two flues at the junction of which each burner is located. The flame from the burner 16, for example, will be in the flue 2. When the flow of air and gases is reversed, the flame from the burner 16 will be in the flue 1 and will 55 heat this flue. When both the burners 16 and 18 are ignited, the flame from one of these burners will heat the flue 2 at all times and the flues 1 and 3 will be directly heated during only one-half of the time. In the same 60 manner the flames from the burners 19, 20 and 17 will heat the flues 3, 4, 5 and 6 when these burners are ignited. The waste combustion gases passing through the flues will keep the walls of the oven at an elevated temperature at all times, and only selected por-

tions of the walls will be raised to intense heat.

The pitch may be added to the oven gradually and continually during the coking operation until the desired charge has been 70 added to the ovens. The pitch may be added as a continuous stream. As an alternative method small increments of pitch may be added to the ovens from time to time. Each increment may represent but an inch or two 75 of pitch over the entire area of the oven. On the other hand, the entire charge of pitch may be charged to the oven in three or four charges, with a lapse of two or three hours 80 between charges. All of the charges may be uniform or it may be advantageous to vary the size of the charge as the coking operation progresses.

The drawings indicate an operation in 85 which several ovens of a battery are charged in rotation and in which high melting point pitch is charged to each oven in four separate portions. Each oven indicates a different stage of the coking operation. The 90 burners 16 of the oven A are lighted and the flues 1a and 2a are heated. Burners 18 are then lighted, flues 2a are brought to an intense heat as indicated in the drawings, and flues 1a and 3a are heated, and the first 95 charge is added to the oven.

After about two hours, burners 19 are ignited as indicated at oven B, and flues 2b and 3b are brought to intense heat and the second portion of the charge is added to the 100 oven. Then burners 20 are lighted, the third portion of the charge is added to the oven as shown at oven C, and flues 4c are brought to intense heat.

The fourth portion of the charge may be 105 somewhat smaller than previous charges in order to prevent the oven from foaming over. The drawings show oven D after the fourth charge is added and with flues 5d brought to an intense heat by the burners 17. When the coking is so controlled that the first portion of the charge is completely coked by 110 the time this fourth portion is added to the oven, burners 16 may be extinguished since flues 2d need no longer be maintained at intense heat. Flues 1d will then only be heated by the waste combustion gases which pass through them in going to flue 14 and the regenerator.

As the coking proceeds burners 18 may be 115 extinguished. Then only flues 4e and 5e will be at intense heat as shown at oven E. When the coking is finally completed the burners may all be extinguished, or the gas flow through them greatly reduced, and the charge of coke may be pushed from the 120 oven, or removed in any suitable way. Before pushing, burners 16, or both burners 16 and 18, may be lighted so that when the oven is pushed the bottom of the oven will be hot and ready for charging. The oven is 125 130

then again charged as shown at oven A and the cycle is repeated.

As an alternative method it may be desirable to keep the bottom burners burning at all times to keep the bottom of the oven hot and ready for recharging, and to extinguish only the upper burners when they are no longer needed for heating.

The drawings are merely illustrative as to the number of ovens which may be employed in series, the type of coking vessel that may be used, and as to the manner of supplying the pitch to the ovens. The time necessary for coking a full charge of pitch or a partial charge is dependent upon the size of the oven, the nature of the heating flues, the melting point and volatile content of the pitch, etc.

I claim:

20 1. The method of coking a batch of pitch, which comprises gradually adding the pitch to a coking vessel, heating it indirectly so as to coke it, maintaining the pitch and the coke substantially stationary during the coking 25 operation and as the mass of coke formed increases by the addition of pitch and its conversion to coke, changing the zone to which heat is applied so that the most intense heat is applied to the added material which has 30 not formed coke so as to convert it to coke.

2. The method of coking a batch of pitch, which comprises gradually adding the pitch to a coking vessel, heating it indirectly so as to coke it, maintaining the pitch and the coke 35 substantially stationary during the coking operation and as the mass of coke formed increases by the addition of pitch and its conversion to coke, changing the zone to which heat is applied so that the most intense heat 40 is applied to the added material which has not formed coke in order to convert it to coke, and cooling the gases and vapors thus produced to recover oils therefrom.

3. The method of coking pitch in a coke 45 oven, which comprises gradually adding pitch to a substantially stationary mass of pitch in the oven while coking the mass, and extending the zone of intense heating of the walls of the oven from the bottom upwardly as the coking 50 layer of the mass rises in the oven.

4. The method of coking pitch, which comprises heating the bottom portion of a coke oven, gradually adding pitch thereto, maintaining the added pitch substantially stationary and converting it to coke, and continuing to add pitch gradually to the oven and to build up a mass of coke in the oven, and extending the zone of intense heating of the walls of the oven from the bottom upwardly 60 as the level of the pitch being coked rises within the oven.

5. The method of coking pitch, which comprises adding a small amount of pitch to an oven and applying heat to the sole of the oven 65 whereby a substantially stationary coking

mass is formed, adding increments of pitch to the oven at intervals while coking the substantially stationary coking mass, and as the level of the pitch being coked rises within the oven, extending the zone of intense heating 70 of the walls of the oven from the bottom upwardly.

6. The method of coking a batch of pitch, which comprises gradually adding the pitch to an oven while heating the oven indirectly 75 whereby a substantially stationary coking mass is formed, and the stationary mass is converted to coke, and applying the greatest heat to the oven in a zone adjacent to pitch which is being converted to coke.

7. The method of converting pitch to coke, which comprises gradually adding pitch to an oven, maintaining the added pitch substantially stationary, applying heat to the oven so as to convert the pitch in the oven to coke while continuously adding pitch to the oven, and as pitch is added and converted to coke changing the zone to which the most intense heat is applied so that the most intense heat is applied to the walls of the oven adjacent to material which is being coked.

8. The method of converting a batch of pitch to coke, which comprises coking the pitch in an oven by applying heat to the bottom of the oven, adding increments of the pitch to the oven at intervals as the material in the oven is coked while heating the oven, maintaining the pitch and the coke substantially stationary during the coking operation, and changing the zone of greatest heat as the oven becomes filled with pitch and coke so that the greatest heat is applied to the oven above the coke which has been formed in the oven and adjacent to the material being coked.

9. The method of converting pitch to coke, which comprises gradually adding pitch to an oven while converting the pitch in the oven to coke, maintaining the pitch and the coke substantially stationary during the coking operation, heating only lower portions of the oven during the early portion of the coking operation as pitch is being added to the oven, heating the upper portion of the oven to an intense heat as the last of the pitch is added to the oven, and maintaining the upper portion of the oven at an intense heat until the coking is completed.

10. The steps in the method of converting pitch to coke, which comprise adding pitch to an oven containing coke newly formed from pitch and applying heat through the walls of the oven adjacent to the added pitch so as to convert the pitch to coke, subsequently decreasing the application of heat to that portion of the walls of the oven adjacent to this newly formed coke while applying intense heat to another portion of the walls of the oven adjacent to pitch added to the oven while the aforementioned pitch was being

coked, and maintaining the pitch and the coke substantially stationary during the coking operation whereby a solid compact coke suitable for metallurgical purposes is obtained.

- 5 11. The method of coking pitch, which comprises gradually adding pitch to an oven, maintaining the pitch substantially stationary in the oven and coking it therein, maintaining a zone of intense heating adjacent
- 10 the coking pitch, and extending the zone of intense heating from the bottom upward as the oven becomes filled.

In testimony whereof I affix my signature.
